UNITED STATES PATENT OFFICE.

EDWIN H. BELL, OF CHICAGO, ILLINOIS.

PROCESS OF MANUFACTURING TIE-PLATES.

938,109.

Specification of Letters Patent. Patented Oct. 26, 1909.

Application filed August 26, 1908. Serial No. 450,290.

To all whom it may concern:

Be it known that I, EDWIN H. BELL, a citizen of the United States, and a resident of Chicago, in the county of Cook and State 5 of Illinois, have invented certain new and useful Improvements in Processes of Manufacturing Tie-Plates; and I do hereby declare that the following is a full, clear, and exact description thereof, reference being 10 had to the accompanying drawings, and to the letters of reference marked thereon, which form a part of this specification.

This invention relates to improvements in the process of manufacturing railway tie- 15 plates of rolled steel and of that kind in which the tie-plate is provided on its upper surface with a transverse rib forming a rail-abutting shoulder.

My invention consists in the matters here- 20 inafter described and pointed out in the appended claims.

My improved process may be described in general terms as consisting in the steps of passing a bar of metal successively between pairs of rolls, one of which is grooved to form flanges on the lower surface of the plate, thereby step-by-step converting the bar into a continuous blank having longitudinal flanges on one surface, and then passing 25 the blank between a pair of rolls, one of which completes the formation of the longitudinal flanges while the other is provided with transverse grooves spaced apart distances corresponding with the desired 30 length of the tie-plate, thereby displacing the metal of the tie-plate bar longitudinally to form said rib, said grooves being of different depths at different parts, whereby the metal in each rib is displaced longitudinally 35 thereof to make parts of said rib of unequal height and finally cutting the continuous blank into sections to form the individual tie-plates.

My invention may be more readily understood by reference to the accompanying drawings illustrating the several steps constituting my novel process, in which drawings,—

Figure 1 is an end view of a billet of 50 metal. Fig. 2 is a view in elevation of the adjacent parts of the peripheries of a pair of rolls between which the billet is first passed. Fig. 3 is a view similar to Fig. 2

showing a pair of rolls between which the billet is subsequently passed. Fig. 4 is a 55 sectional view of the billet after having passed between several pairs of rolls. Fig. 5 is a cross-sectional view of the billet at a later period of its treatment. Fig. 6 is a sectional view of the billet prior to being 60 passed through the last pair of rolls. Fig. 7 is a longitudinal sectional view of the blank into which the billet has been converted, showing the adjacent peripheries of the last pair of rolls, which form the shoulders on the blank. Fig. 8 is a view in elevation of the last pair of rolls, which form the shoulders on the blank, the blank being shown in transverse cross-section. Fig. 9 is a fragmentary cross-section of the upper 70 roll illustrated in Fig. 7, showing the recesses by means of which the rounded projections are formed on the rib. Fig. 10 is an end elevation of the completed tie-plate. Fig. 11 is an end elevation of a completed 75 tie-plate of somewhat different form. Fig. 12 is a perspective view of the form of tie-plate shown in Fig. 10. Fig. 13 is a perspective view of the form of tie-plate shown in Fig. 11.

As shown in the said drawings, Fig. 1 shows the cross-sectional form of a metal billet 5 which is to be converted by my improved process into tie-plates. 6 and 7 designate a pair of rolls between which the 85 billet is passed, the roll 6 having three ribs 8, 8, 8, on its periphery while the roll 7 has four ribs 9, 9, 9, 9, on its periphery. The co-operating ribs on the rolls serve to impart to the billet a cross-sectional form 90 such as is shown in Fig. 2. Said rolls 6 and 7 are provided with side flanges 10 and 11, respectively, which operate to prevent the billet from spreading laterally as the same passes through or between the rolls. A sec- 95 ond pair of rolls 15 and 16 is employed to impart to the billet 5 a cross-sectional form, such as is shown in Fig. 3, the roll 15 having the four grooves 17, 17, 17, 17 on its periphery while the roll 16 has the four ribs 100 18, 18, 18, 18 on its periphery, the grooves on the said roll 15 being arranged oppositely of the ribs on the roll 16 in such a manner that the metal displaced by the said 105 ribs is pressed into the grooves of the roll 15. In Figs. 4, 5 and 6, the billet 5 is shown

as it appears in cross-section after having passed between succeeding pairs of rollers, each subsequent pair being arranged nearer together, in order that the billet will be 5 gradually flattened and the peripheries of the rolls in the successive pairs are of such shape as to gradually impart to the billet longitudinal grooves on one surface and longitudinal alining flanges on its other surface, the said flanges being in line with the said grooves. The successive pairs of rolls between which the billet has passed in being converted into the cross-sectional form shown in Fig. 6, form longitudinal raised 10 portions between the grooves on the upper surface of the plate, such raised portions being formed to enable the metal to be longitudinally displaced in the subsequent steps by which the ribs are formed. The final 15 form is imparted to the billet 5 by means of the rolls 20 and 21, illustrated in Figs. 7 and 8 of the drawings. The upper one of the said rolls, designated by the reference number 20, is provided upon its periphery 20 with longitudinally arranged ribs 22, 22 which are adapted to displace the metal of the plate to form longitudinal depressions or grooves in the upper face of the bed plate. For forming the transverse rib 25 upon each of the said tie-plates transverse grooves are provided in the periphery of the upper roll 20, located at longitudinal distances apart equal to the length of a finished plate. Said grooves each consist of concave 30 recesses 23, 24, 25 and 26 (Fig. 9) which are connected with each other by shallower parts of the grooves between them. The recesses 24 and 25, located one on each side of the central longitudinal line of the plate, are 35 of greater depth than the recesses 23 and 26 which are adjacent to the side margins of the plate. The grooves so made, form on the plate a continuous transverse rib 27, Figs. 10 and 12, having rounded projections 40 28, 29, 30 and 31, the projections 28 and 31 which are adjacent to the side margins of the plate and formed by the recesses 23 and 26 being of less height than the projections 29 and 30, formed by the recesses 24 and 25 45 of the said grooves, and all of the said projections being separated by depressions or notches 32, 32, formed by the shallower parts of the transverse groove in the roll. The metal which forms said transverse rib, as 50 55 a whole, is obtained in the rolling operation by displacement endwise of the metal of the plate, while the metal to form the higher projections 29 and 30 of the rib is displaced laterally of the plate or endwise of the groove 60 in the roller, the shallower connecting parts of the said groove, between the concave recesses 23, 24, 25 and 26, permitting such displacement of the metal of the rib longitudinally thereof. In other words, in the rolling op-

eration, sufficient metal is displaced endwise 65 of the plate to form the rib as a whole while the additional quantity of metal required to form the higher rounded projections 29 and 30 is derived by lateral displacement of the metal from the parts of 70 the rib having the lower projections 28 and 31 and at which the metal is depressed between the projections. The longitudinal alining flanges 33, 33 upon the bottom surface of the tie-plate are given a V-form in 75 cross-sectional shape, by means of longitudinally arranged grooves 34, 34 in the periphery of the lower roll 21, said grooves 34, 34 being in line with the ribs 22, 22 upon the upper roll. After the billet has been passed 80 between the last named pair of rolls it is cut transversely adjacent each transverse rib so that the said rib is located adjacent to one end of the plate. The said tie-plate when completed is shown in Fig. 12. 85

In Fig. 13 is shown a completed tie-plate of a different form from that first described, the process of manufacture of which is the same as hereinbefore set forth. The main difference between the two plates consists in 90 the form of the transverse rib which, in the latter case, is continuous, the high and low portions thereof having straight top edges parallel with the body of the plate, instead of being curved or rounded, as in the former 95 case. The lower surfaces of the plates are the same in both cases, but in the latter case the top surface of the tie-plate is flat instead of being longitudinally grooved as in the former case. 100

I claim as my invention:—

1. The process of manufacturing a tie-plate blank having a continuous transverse rib across its upper surface, the height of the rib varying at different points, said 105 process consisting in first rolling a billet of metal into a continuous strip having longitudinal flanges on its bottom surface, and then rolling the strip so as to displace the metal on the top surface of the plate in advance of the rib portion longitudinally to form a continuous transverse rib extending across the rib portion, and to also displace the metal of said transverse rib in the direction of its length to make different parts of 110 said rib of unequal heights. 115

2. The process of manufacturing a tie-plate blank having a continuous transverse rib across its upper surface, the height of the rib varying at different points of its 120 length, said process consisting in first rolling a billet of metal into a continuous strip having longitudinal grooves on its top surface and longitudinal flanges on its bottom surface in line with the grooves, and then rolling the strip so as to displace the metal on the top surface of the plate in advance of the rib portion longitudinally to form a con- 125

tinuous transverse rib extending across the rib portion and having projections intermediate the longitudinal grooves, and to also displace the metal of said transverse rib in the direction of its length to make said projections of unequal heights.

In testimony, that I claim the foregoing as my invention I affix my signature in the

presence of witnesses, this 24th day of August A. D. 1908.

EDWIN H. BELL.
